UNITED STATES PATENT OFFICE.

JOHN E. HUME AND WILLIAM H. KING, OF CLINTON, MASSACHUSETTS, ASSIGNEES TO CROMPTON & KNOWLES LOOM WORKS, OF WORCESTER, MASSACHUSETTS, A CORPORATION OF MASSACHUSETTS.

BOBBIN SUPPORT FOR WEFT-REPLENISHING MECHANISM.

Application filed September 24, 1924. Serial No. 739,692.

This invention relates to improvements in weft replenishing mechanism of the multi-color type and more particularly to the giveways on which the bobbins are held as they await transfer.

In the usual form of multi-color magazine the tip of the bobbin, when in transferring position, is supported by two yieldable supports while the head or butt of the bobbin 10 is supported on the rear side by a yieldable giveaway and on the front side by a fixed and immovable guideway usually formed as an integral part of the frame of the replenishing mechanism. With such a construction 15 breakages occasionally occur due to a bobbin being caught under the transferrer while it is still on the fixed support. It is to be understood that the bobbins are subject to slight variations and that the larger ones 20 sometimes stick in the releasing devices so that they are slower in starting toward transfer position. Under these conditions it is likely that as the transferrer descends it will strike the butt of the bobbin and break the 25 fixed guideway.

It is the principal object of our present invention to provide a yieldable giveaway for the front side of the butt of the bobbin so that should the bobbin be slow in moving 30 down the guideway to transfer position no injury can result if it should be struck by the transferrer.

In attaching the replenishing mechanism to a loom it is essential that the delivery point 35 of the bobbins bear a very definite relation to the lay. In the past the fixed guideway has been used for the purpose of setting the replenishing mechanism, a gauge being provided to fit a portion of the guideway and 40 thus position the replenishing mechanism with respect to the loom. Because of the use that is made of the guideway in setting the loom parts, it is necessary that it shall always bear the same relation to the lay. 45 It is accordingly a further object of our invention to provide a giveaway at this point which shall be incapable of adjustment and which will always return to the same position irrespective of adjustments in any of the 50 other bobbin giveways. In carrying this feature of our invention into effect we find it desirable to make the spring which permits yielding movement of the giveaway considerably stronger than the spring for the rear

giveaway. Unless there is danger of breakage 55 it is desirable that all the yielding for the butt of the bobbin be done by the rear support, the forward support serving as a guide to direct the bobbin into the shuttle.

With these and other objects in view which 60 will appear as the description proceeds, our invention resides in the combination and arrangement of parts hereinafter described and set forth in the claims.

In the accompanying drawings wherein we 65 have shown one form of our invention,

Fig. 1 is a side elevation of the lower portion of a multi-color weft replenishing mechanism having our invention applied thereto,

Fig. 2 is a horizontal section on line 2—2 70 of Fig. 1, looking in the direction of the arrows,

Fig. 3 is a vertical section taken on line 3—3 of Fig. 2 and looking toward the butt 75 of the bobbin, and showing a portion of the lay and the relation that the same sustains to the butt guideways, and

Fig. 4 is a perspective view of the giveaway forming the subject matter of our invention.

Referring to the drawings, it will be seen 80 that we have provided a weft replenishing mechanism having inner and outer frames 10 and 11, respectively, which are held together by tie rods 12. The outer frame 11 is provided with a pair of bobbin tip giveways 13 85 which are of substantially the same construction and each of which comprises a bobbin guide 14 hung on a pair of links or supports 15 and 16, respectively. The inner links 15 have pivotal connection with the frame 11 90 as at 17 and the outer links 16 are pivotally mounted on certain of the tie rods 12. The lower end of each of the links 15 is provided with a slot 18 which receives a bolt 19 by means of which the vertical position of the 95 guide 13 may be varied. Each of the links 15 is also provided with an adjusting screw 20 positioned for engagement with some portion of the frame 11 to afford horizontal adjustment of the giveways 13. Springs 21, 100 which are secured to collars 22 carried by certain of the tie rods 12, are connected to the links 16 and serve to move the giveways 13 toward bobbin supporting position.

The rear support for the butt of the bobbin adjacent the inner frame 10 comprises a lever 23 having a bobbin guideway 24 and pivoted as at 25 to the lower end of link 26,

the upper portion of which is mounted loosely on one of the tie rods. A coil spring 27 has one end held in adjusted position by a collar 28 on one of the tie rods and has the other end thereof connected to the link 26, serving normally to move the lever 23 toward bobbin supporting position. The rear end of lever 23 is bent upwardly as at 29 and carries a pin 30 which has adjustable contact with a screw 31 threaded in a link 32 which is pivoted as at 33 to the frame 10. The giveways hereinbefore described may be substantially of the form shown in Patents Nos. 1,366,950 and 1,495,717. The replenishing mechanism is spaced above a lay 34 which has a binder 35 and a box back 36 to receive shuttle S. The matter thus far described is of the usual construction and forms no specific part of our present invention.

In carrying out our invention we provide a giveway 40 with a bobbin guide or run 41 terminating in a vertical lip 42. Spaced from the run 41 and on the opposite side of frame 10 is an arm 43 integral with the guide and formed with a bearing 44 to receive a stud or other pivot 45 mounted on said frame. The arm 43 is connected to the guideway 41 by a neck 46 having an upper face 47 positioned to engage the under side of the frame 10. The arm 43 is also provided with a boss 48 which receives the lower end of a spring 49 the upper end of which is held to a fixed part of the frame 10 as at 50.

The stud or pivot 45 is only slightly to one side of a vertical line passing through the lip 42 so that the latter will always be above the shuttle binder when swinging on the pivot. The guide 41 is in substantial alignment with a flange 51 formed on the frame 10 and so placed as to direct the bobbins into the guide 41. Spring 49 is much stronger than spring 27 and in all normal operations of the replenishing mechanism the bobbins will be supported jointly by the lever 23 and the lip 42 before the transfferer 52 starts downwardly. However, should the bobbin fail to be properly positioned and be caught by the transfferer the giveway 40 will move to the left as indicated in dotted lines in Fig. 3.

It will be observed that the giveway 40 is entirely free of any adjustment and that spring 49 will always return surface 47 to the lower portion of the frame 10 thus keeping the giveway in the same normal position.

Because of this construction it is possible to set the replenishing mechanism with respect to the lay 34 by means of a gauge block as hereinbefore explained.

From the foregoing it will be seen that we have provided a weft replenishing mechanism with a yielding bobbin release sufficiently strong to remain immovable during all normal operations of the mechanism but capable of movement to prevent breakage.

It will also be noted that the giveway is pur-

posely left free from all adjustments so that the operatives cannot vary the position of the same and thus give the mechanism an improper setting with respect to the lay. Also, it will be seen that the pivot 45 is so placed that the guide 41 will have only a very slight downward motion as it moves, but said pivot 45 is so placed that it will permit yielding of the giveway for any position of the bobbin where the latter can be struck by the transfferer.

Having thus described our invention it will be apparent that changes and modifications may be made therein by those skilled in the art and we do not wish to be limited to the details herein disclosed, but what we claim is:

1. A support for the butt end of a bobbin for a weft replenishing mechanism, said support having a guideway for the bobbin terminating in a substantially vertical lip, a spaced supporting arm, and a neck connecting the guideway and the supporting arm, all of said parts being integral, the neck adapted for engagement with a portion of the replenishing mechanism and the arm having a bearing therein for pivotal mounting of the guideway remote from the neck.

2. In weft replenishing mechanism, a pair of yieldable supports for the butt of the bobbin, a relatively light yielding device connected to one of said supports, a relatively heavy yielding device connected to the other support, said yielding devices holding the supports in normal position and acting to return said supports after a yielding movement to the same position with respect to the replenishing mechanism, the support having the relatively light yielding device being yieldable under the normal operation of the replenishing mechanism while the support connected to the relatively heavy yielding device remains normally stationary but is yieldable under abnormal conditions of the mechanism.

3. In a weft replenishing mechanism for looms, a support for the rear of the butt of the bobbin, relatively light yielding means to hold said support in normal position, a second support for the front of the butt of the bobbin, and relatively heavy yielding means operatively connected to said second named support to hold the same in normal position to cause said second support to offer a relatively high resistance to movement.

4. In a weft replenishing mechanism for looms a pair of yielding supports for the bobbin always returnable after yielding movement to the same position with respect to the replenishing mechanism, a yielding device connected to each support holding the supports in normal position, one of said yielding devices being weaker than the other and offering less resistance to movement of the corresponding support than is offered by the other yielding device whereby said other

yielding device remains in substantially the same position for all normal operations of the mechanism.

5. In a weft replenishing loom, weft replenishing mechanism, a lay, a pair of yielding supports for the butt of the bobbin, a pair of yielding supports for the tip of the bobbin, relatively weak yielding means to hold one support for the butt of the bobbin in 10 normal position, relatively strong yielding means to hold the other support for the butt of the bobbin in yielding position, said other support for the butt of the bobbin corresponding to the strong yielding means being 15 held in normal position by a force greater than the force holding the first named support for the butt of the bobbin in normal position, said other support being yieldable under abnormal conditions only and remaining 20 normally at rest and returnable always to the same position with respect to the replenishing mechanism and the lay after a yielding movement.

6. In a weft replenishing mechanism for 25 looms, a pair of yielding supports for the butt of the bobbin, a pair of yielding supports for the tip of the bobbin, said supports being independent of one another but always returnable after yielding movement to 30 the same position with respect to the replenishing mechanism, a yielding device connected to each support holding the support in normal position, one of the yielding devices for the corresponding support for the bobbin 35 butt being relatively weak and the other yielding device for the other support for the bobbin but being relatively stronger than the first named yielding device, the said other de-

vice and corresponding bobbin butt support remaining substantially stationary for all 40 normal operations of the loom and the first named support for the bobbin butt yielding.

7. In a weft replenishing mechanism for 45 looms, a pair of spaced independently movable surfaces to engage the butt of a bobbin on opposite sides thereof, said surfaces being returnable to the same positions after each movement thereof, and a yielding means operatively connected to each surface, said means being of unequal strength and acting 50 to hold the surfaces in normal position with different degrees of firmness, one of said means acting with a greater force than the other means, so that the surface corresponding thereto will remain stationary while the 55 other surface yields during the normal operation of the mechanism.

8. In a weft replenishing mechanism for 60 looms a pair of yielding supports for opposite sides of the same end of the bobbin always returnable after yielding movement to the same position with respect to the replenishing mechanism, a yielding device connected to each support holding the supports in 65 normal position with different degrees of firmness, one of said yielding devices being weaker than the other and offering less resistance to movement of the corresponding support than is offered by the other yielding device whereby said other yielding device remains in substantially the same position for all normal operations of the mechanism.

In testimony whereof we have hereunto affixed our signatures.
